AUTOMATIC VOLUME CONTROL SYSTEM

Norton F. Shofstall, Stratford, Conn., assignor to
General Electric Company, a corporation of
New York

Application December 8, 1938, Serial No. 244,621

13 Claims. (Cl. 250—20)

My invention relates to automatic volume control systems for signaling apparatus, such as radio receivers, and it has for one of its objects to effect certain improvements therein with respect to the avoidance of overloading of the controlled stages of the apparatus.

My invention relates more particularly to automatic volume control systems in which the control potential for regulating the gain of the various stages of the receiver is supplied thereto through individual circuits employing the usual filter resistors for suppressing audio and radio potentials which appear on those conductors.

One of the objects of my invention is to reduce overloading produced by reason of grid current flowing in these resistors.

Another object of my invention is to reduce the effects of such overloading through redistribution of the control potentials supplied to regulate the gain of the several amplifier stages employed in the receiver.

A further object of my invention is to provide an automatic volume control arrangement in which the receiver does not cut-off as the tuning 25 of the receiver is adjusted to proximity with a strong signal and one which, therefore, allows the automatic frequency control system of the receiver to function in normal manner accurately to tune the receiver to a desired signal whether 30 the signal be relatively weak or very strong.

The novel features which I believe to be characteristic of my invention are pointed out with particularity in the appended claims. My invention itself, however, both as to its organization 35 and method of operation together with further objects and advantages thereof may best be understood by reference to the following description taken in connection with the accompanying drawing in which Fig. 1 represents an embodiment of my invention and Fig. 2 represents a 40 modification thereof.

Referring particularly to Fig. 1 of the drawing, my invention is illustrated as embodied in a 45 superheterodyne type of radio receiver in which an antenna ground system 10, 11 is connected to the input circuit of a tunable radio frequency amplifier, represented conventionally by the rectangle 12 which may comprise one or more stages 50 of amplification. The output of the radio frequency amplifier 12 is supplied to additional tunable stages of amplification, represented conventionally by the rectangle 13, which may include a converter for changing the oscillations 55 of signal frequency to oscillations of intermediate

frequency and one or more stages of intermediate frequency amplification.

The output of the last stage of intermediate frequency amplification included in the apparatus 13 is supplied to a frequency discriminatory network comprised by a transformer 14 having a primary winding 15 and a center-tapped secondary winding 16. The primary winding 15 and the secondary winding 16 are tuned to the intermediate frequency by the respective condensers 17 10 and 18.

Each end of the transformer secondary winding 16 is connected to an anode element 19, 20 of a respective diode rectifier 21, 22. The diodes 21 and 22 have cathode elements 23, 24 which 15 are connected together through a load resistor 25. A radio frequency choke 26 connects the center-tap of the secondary winding 16 with a center-tap on the resistor 25. A condenser 27 connects the high potential end of the transformer primary winding 15 with the center-tap 20 of the transformer secondary winding 16. The cathode 24 of the diode 22 is connected directly to ground as shown while the cathode 23 of the diode 21 is maintained at ground potential for 25 currents of intermediate and audio frequency by the use of a condenser 28.

The potential appearing across the lower half of the load resistor 25 is supplied through a condenser 29 to an audio frequency amplifier, represented conventionally by the rectangle 30, which 30 may include one or more stages of audio frequency amplification. The output of the audio frequency amplifier is supplied to a translating device 31 here shown by way of illustration as a 35 loud speaker.

The connection of the transformer 14 in the manner shown provides a frequency discriminatory network whose operation is explained in detail in the October 1935 issue of the Proceedings 40 of the I. R. E. beginning at page 1125. An automatic frequency control potential appears between ground and the upper terminal of the resistor 25. This potential is supplied through an electrical conductor 32 to an automatic frequency control tube, included in the apparatus 45 13, which operates in a manner well-known in the art to maintain substantially constant the oscillations supplied to the intermediate frequency amplifier.

A portion of the voltage appearing across the lower half of the resistor 25 is supplied through the conductors 33 and 34 and through a filter comprised by a resistor 35 and a condenser 36 to the control electrode of one or more of the 50 55

several electron discharge devices included in the converter stage and the intermediate frequency amplifier stages of the apparatus 13. This automatic volume control potential operates in well-known manner to maintain substantially constant the output of the intermediate frequency amplifier though the input signal strength may change over a wide range of values. A larger proportional part of the potential appearing across the lower half of the resistor 25 is supplied through the conductors 37 and 38 and through a filter comprised by a resistor 39 and a condenser 40 to the control electrode of one or more of the electron discharge devices included in the radio frequency amplifier stages of the apparatus 12. The value of this automatic volume control potential is chosen several times larger than that supplied to the converter and intermediate frequency amplifier for the purpose of preventing the overloading of the radio frequency amplifier and converter stages when the receiver is tuned exactly to resonance with a very strong signal which may, for example, be of the order of two volts or more at the antenna input terminals.

The automatic volume control system thus far considered performs meritoriously as long as the receiver is accurately tuned to very close resonance with a signal. However, as soon as the receiver is slightly detuned from or is initially tuned only to proximity with a strong signal, the highly selective circuits of the intermediate frequency amplifier greatly reduce the automatic volume control potential appearing in the conductors 34 and 38. This permits the radio frequency amplifier 12 to operate in overloaded condition at high gain and causes the converter, and such other of the radio frequency stages of amplification as precede the converter and are biased through the conductor 34, thereupon to overload by having its control grid driven into the positive bias region where the grid draws current. The grid current flows through the resistor 35 and the lower portion of the resistor 25 to produce across these resistors a potential drop whose polarity is in a direction further to reduce the gain of the intermediate frequency stages of amplification by driving them toward cutoff. Little or no signal energy thereafter passes to the output of the intermediate frequency amplifier and little or no automatic frequency control or automatic volume control potentials are developed across the resistor 25. This renders the automatic frequency control arrangement so unresponsive that the latter in effect is deenergized and the receiver fails to "pull-in" to the strong signal.

To overcome this condition of operation, advantage is taken of the fact that the converter normally overloads more than the radio frequency stages of amplification. A diode rectifier 42 is connected between the automatic volume control conductors 34 and 38, the anode element 41 of the rectifier being connected to the automatic volume control conductor 38 while the cathode element 43 is connected through a resistor 44 to the automatic volume control conductor 34.

With the diode rectifier 42 connected in this manner, the relatively small radio frequency amplifier grid current and the relatively larger converter control grid current which flows when the receiver is tuned only to proximity with a strong signal makes the automatic volume control conductor 34 negative with respect to the automatic

volume control conductor 38 thereby to render the diode anode 41 positive relative to the diode cathode 43. Grid current which previously flowed through the resistor 35 now flows from ground to the converter control grid through a series circuit including the resistors 25 and 39, the conductor 38, the diode rectifier 42 and the conductor 34. This decreases the negative bias produced across the resistor 35 and increases the negative potential of the automatic volume control conductor 38 thus biasing the radio frequency amplifier included in the apparatus 12 toward cut-off to limit its output and thereby reduce the overload on the converter. The diode 42 has a relatively low anode to cathode resistance and, as long as the diode passes current, the conductors 34 and 38 are effectively tied together electrically and operate at substantially the same potential above ground. This prevents the intermediate frequency amplifier from being biased to or toward cut-off and allows the generation of some automatic frequency control potential and automatic volume control potential. The automatic frequency control system thereupon operates to change the tuning of the oscillatory circuit of the converter more accurately to tune the receiver to resonance with the strong signal. When this occurs, a larger automatic volume control potential is developed across the resistor 25 and the gain of the radio frequency amplifier and converter is reduced. This removes the overload on the radio frequency amplifier and converter thereby to improve the fidelity of reproduction of the received signal.

The cathode 43 of the diode 42 is normally energized with alternating current. The resistor 44 is inserted between the conductor 34 and the diode 42 to form, in conjunction with the condenser 36, a ripple filter for the purpose of reducing alternating current pulsations which might otherwise be induced on the automatic volume control conductors 34 and 38 by the alternating current energization of the cathode 43.

It has been found that without the diode 42 connected in circuit, the automatic frequency control tube would not cause the receiver to "pull-in" to resonance with a strong 1400 kc. signal (having a strength of two volts at the antenna) whenever the receiver was tuned to more than about 10 kc. off resonance. With the diode 42 connected as shown, the same receiver would pull in to the same signal when the receiver was tuned as much as 20 kc. off resonance. The failure of a receiver to pull in to resonance with a selected signal is particularly serious in the increasingly popular motor tuned or trimmer condenser tuned type of radio receiver where a person tunes the receiver by merely pushing a selected push-button. The mechanical error in electric motor tuning may be 5 or 10 kc. which, in the absence of my invention, is sufficient to render the receiver inoperative to receive very strong local stations. This condition of operation applies in like manner to trimmer condenser tuning where the condensers are improperly adjusted or, having been properly adjusted, have drifted somewhat from their initial setting.

The several amplifiers of the Fig. 1 arrangement are self-biased in a manner well known in the art by the use of a suitable cathode biasing resistor and parallel connected condenser, not shown. In Fig. 2, I have shown how my invention may be used where it is desirable to provide some control of the sensitivity of the radio receiver. The Fig. 2 arrangement dispenses with

the necessity of biasing the amplifier stages in their cathode circuit and allows the cathodes of the several amplifier electron discharge devices to be directly connected to ground. Elements in 5 this figure corresponding to like elements of Fig. 1 are designated by like reference characters. The apparatus represented conventionally by the rectangle 45 of this figure includes, in addition to the apparatus 13 of Fig. 1, the frequency discriminatory network of Fig. 1 comprised by the transformer 14 and interconnected circuit, and the diode rectifiers 21 and 22.

In the Fig. 2 embodiment, two diode rectifiers are included in a common envelope 46. One of 15 the diode anodes 47 is connected to the automatic volume control conductor 34 while the second diode anode 48 is connected to the automatic volume control conductor 38. A source of substantially constant unidirectional potential 20 49, 50 is connected across a voltage divided resistor 51, a point 49 of which is grounded. A supplementary voltage divider resistor 52 is connected upon closure of a manually operated switch 53 across a portion of the resistor 51. 25 The cathode 54 of the electron discharge device 46 is connected to a point on the resistor 51 negative with respect to ground. The cathode 55 of the device 46 is connected to a point on the resistor 52.

30 The unidirectional potential source 49, 50 produces a flow of current through two circuits, the first of which may be traced from the terminal 49 through ground, through the lower portion of the resistor 25, the conductor 37, the resistor 39, the diode anode 48, the diode cathode 54, and through a conductor 56 to a point on the resistor 51 negative with respect to the terminal 49. The second circuit may be traced from the terminal 49 through ground, through the lower portion of the resistor 25, the conductor 33, the resistor 35, the diode anode 47, the diode cathode 55, and through the left-hand portion of the resistor 52 to a point on the resistor 51 negative with respect to the terminal 49. The current flowing in each of these two circuits produces a 40 potential drop across the resistors 35 and 39 thereby to provide a normal operating bias for the control electrodes of the several amplifier stages included in the apparatus 12 and 45. The 45 switch 53 when closed increases the current flow through the resistor 35 thereby to bias the amplifier stages included in the apparatus 45 toward cut-off for the purpose of reducing the sensitivity of the radio receiver.

50 The diode 42 in Fig. 2 operates in the manner of and for the same purpose as the corresponding diode in the Fig. 1 arrangement. It will be apparent that the diode rectifiers 47, 55 and 48, 54 serve only to provide a normal operating bias 55 for the amplifiers 12 and 45. Current flow through either of these rectifiers ceases when its anode becomes negative with respect to its cathode as would occur during the times when more than a relatively small automatic volume control potential is developed across the resistor 25 or when the grid current through the resistors 35 and 39 increases above a predetermined value.

55 It will be evident from the preceding description of my invention and its operation that by the term "strong signal" I refer to any signal whose strength is such that at the location of the receiver it causes the grid of a radio frequency amplifier tube or a converter tube or both 60 to draw grid current when the receiver is tuned

to some frequency within a frequency range on either side of and including the signal.

While I have illustrated particular embodiments of my invention, I do not wish to be limited thereto since many modifications may be 5 made in the circuit elements employed and in their arrangement and I, therefore, contemplate by the appended claims to cover any such modifications as fall within the true spirit and scope of my invention.

10 What I claim as new and desire to secure by Letters Patent of the United States is:

1. The combination, in a radio receiver, of a plurality of amplification stages connected in cascade, means automatically to reduce the amplification of said stages in response to increasing intensities of signal currents supplied thereto, and means responsive to the over-loading of a later one of said stages in the cascade connection to further reduce the amplification 20 of an earlier stage in the cascade connection.

2. The combination, in a radio receiver, of a plurality of amplifier stages connected in cascade, means automatically to reduce the amplification of said stages in response to the increasing 25 intensity of a received signal, said means more greatly reducing the amplification of earlier stages than later stages in said cascade connection, and means responsive to the over-loading of a later stage for further reducing the 30 amplification of an earlier stage.

3. In a radio receiver, the combination of a radio frequency amplifier, a frequency converter, and an intermediate frequency amplifier connected in cascade in the order named, means 35 automatically to reduce the gain of each of said amplifiers in response to the increasing intensity of a received signal, and means responsive to the overloading of said converter for reducing the gain of said radio frequency amplifier.

4. In a radio receiver, the combination of a radio frequency amplifier, a frequency converter, and an intermediate frequency amplifier connected in cascade in the order named, means automatically to reduce the gain of each of said 45 amplifiers in response to the increasing intensity of a received signal, a unilateral current conducting device, means to control the amplification of said radio frequency amplifier in accordance with the conductivity of said unilateral 50 conducting device, and means responsive to the overloading of said converter for varying the conductivity of said device.

5. In a radio receiver, the combination of a radio frequency amplifier, a frequency converter, and an intermediate frequency amplifier connected in cascade in the order named, means automatically to reduce the gain of each of said 55 amplifiers in response to the increasing intensity of a received signal, said means more greatly reducing the gain of said radio frequency amplifier than said intermediate frequency amplifier, a unilateral current conducting device, and means responsive to the overloading of said converter for causing said device to become conductive to reduce the gain of said radio frequency 60 amplifier.

6. The combination in a radio receiver, of a radio frequency amplifier, a frequency converter, and an intermediate frequency amplifier connected in cascade in the order named, means automatically to reduce the gain of each of said 70 amplifiers and of said converter in response to the increasing intensity of a received signal, said means more greatly reducing the gain of 75

said radio frequency amplifier than said intermediate frequency amplifier, a unilateral current conducting device, and means responsive to the overloading of said converter for causing said device to become conductive thereby equally to reduce the gain of each of said amplifiers and said converter.

7. The combination, in an automatic volume control system, of a plurality of electron discharge stages connected in cascade, each of said stages having an amplification control electrode, a rectifier connected to the output of the last of said stages, individual circuits connected between the output of said rectifier and each of said amplification control electrodes whereby the potential on each of said control electrodes is controlled by said rectifier, a resistor in each of said circuits, and means responsive to current flowing in one of said resistors to interconnect said circuits thereby to pass a portion of said current through the resistor of the other circuit whereby the potential produced by said current flowing in said other resistor is effective on the control electrode of the stage to which said resistor is connected.

8. The combination, in an automatic volume control system, of a plurality of electron discharge stages connected in cascade, each of said stages having an amplification control electrode, a rectifier connected to the output of the last of said stages, individual circuits connected between the output of said rectifier and each of said control electrodes whereby the potential on each of said electrodes is controlled by said rectifier, a resistor in one of said circuits, and means responsive to current flowing through said resistor for interconnecting said circuits at points thereon adjacent said control electrodes.

9. In combination, a pair of cascade connected amplifiers, each of said amplifiers having a grid and a cathode, means to bias the grid of each amplifier negative with respect to the respective cathode by an amount dependent upon the intensity of currents amplified thereby, one of said grids being biased more negatively with respect to its respective cathode than the other grid is biased negatively with respect to its respective cathode, and means responsive to increase in intensity in said amplified currents beyond a predetermined value to equalize the bias voltage on said grids with respect to said cathodes.

10. In combination, a plurality of cascade connected amplifiers having a control electrode and a cathode, means to rectify the output from the last of said amplifiers and to supply a portion of the rectified potential between the grid and cath-

ode of each of said plurality of amplifiers, the potential supplied between the grid and cathode of one amplifier being greater than that supplied between the grid and cathode of a different of said amplifiers, and means to equalize said last two-mentioned voltages in response to increase in intensity of current amplified by said amplifiers beyond a predetermined value.

11. In combination, a plurality of cascade connected amplifiers, each of said amplifiers having a control electrode and a cathode, means to rectify the output from the last of said amplifiers and to supply the rectified potential to a resistor, conductors extending from different points on said resistor to each of said grids, and means including said conductors to bias each grid negatively with respect to its respective cathode, one grid being biased more negatively than another, and means responsive to current in one of said conductors to connect said conductors together thereby to equalize the voltage on the corresponding grids.

12. In combination, a plurality of cascade connected amplifiers, each of said amplifiers having a control electrode and a cathode, means to rectify the output from the last of said amplifiers and to supply the rectified potential to a resistor, conductors extending from points of different potential on said resistor to corresponding grids of said amplifiers, a diode connected between said conductors and so poled with respect to the potential between said conductors that it is normally non-conductive, and means to render said diode conductive in response to current in one of said grids.

13. In combination, a plurality of cascade connected amplifiers, each of said amplifiers having a control electrode and a cathode, means to rectify the output from the last of said amplifiers and to supply the rectified potential to a resistor, conductors extending from points of different potential on said resistor to corresponding grids of said amplifiers, a diode connected between said conductors and so poled that it is normally non-conductive, resistances connected in the respective conductors between said diode and said first-mentioned resistor whereby when current flows in the less negative of said conductors due to grid conduction in the respective amplifier, the cathode of said diode becomes negative relative to its anode, thereby reducing the current in the resistance in said one conductor and increasing current in the resistance in the other conductor thereby increasing the negative voltage on the other grid.

NORTON F. SHOFSTALL. 55
